UNITED STATES PATENT OFFICE.

GEORGE R. HECKLE, OF MONTREAL, QUEBEC, CANADA.

PILE SHELL OR CASE.

1,366,179.

Specification of Letters Patent. Patented Jan. 18, 1921.

Application filed December 9, 1916, Serial No. 136,069. Renewed September 1, 1920. Serial No. 407,506.

To all whom it may concern:

Be it known that I, GEORGE R. HECKLE, of the city of Montreal, in the Province of Quebec, Dominion of Canada, have invented certain new and useful Improvements in Pile Shells or Cases; and I do hereby declare that the following is a full, clear, and exact description thereof.

My invention relates particularly to the shells for piles of the Raymond type in which the shell is driven by a core receiving the direct impacts and withdrawn when the shell has been sunk to a sufficient depth to sustain the load it is desired to carry when charged with a cementitious filling. It may be applied however with advantage to shells of sufficient rigidity to be driven by direct impact.

The object of the invention is to provide a pile member of the nature above mentioned capable of offering maximum resistance to an outside pressure and at the same time possess sufficient rigidity to, if desired, be driven by the impacts of a pile-driver acting directly thereon.

To this end the invention may be said to consist, broadly, of a corrugated shell with its corrugations running longitudinally, and having the functions of a beam imparted to each of its corrugations by supporting stiffening rings suitably spaced within the shell and connected securely to the inner curves. As each corrugation functions as a beam the shell offers maximum resistance to outside pressure; and at the same time the rings afford means to sustain the abrasive action of the core when one is used. A further feature of the invention is a permanent coating or casing of cementitious material on the outside surface of the shell. The purpose of this coating is to afford a permanent protection for the metal and include the metal in the pile as a permanent reinforcement. If desired the corrugated member may be of expanded metal or other mesh, or plain sheet-metal. This shell may be of sufficient length to act as a pile or, to meet greater depths, it may be made in sections and the reinforcement metal be extended beyond the ends to effect a bond between contiguous sections.

For full comprehension, however, of my invention reference must be had to the accompanying drawings in which similar reference characters indicate the same parts, and wherein:

Figure 1 is a side elevation of my improved pile shell with a core fitted therein ready for driving; the shell being partly broken away for purposes of illustration; 60

Fig. 2 is a similar view with the core removed;

Fig. 3 is a similar view to Figs. 1 and 2 and illustrating a complete pile constructed according to this invention, driven in the 65 ground;

Fig. 4 is a transverse sectional view taken on line 4—4 Fig. 1;

Fig. 5 is a similar view to Fig. 4 with the core removed, the section being taken on line 70 5—5 Fig. 2;

Fig. 6 is a horizontal sectional view taken on line 6—6 Fig. 3;

Fig. 7 illustrates in part elevation and part sectional views, two sections of a pile 75 showing particularly their connection and the core for driving a sectional pile constructed according to my invention; and

Figs. 8 and 9 are fragmentary vertical sectional views of the complete shell un- 80 filled; and

Figs. 10 and 11 are detail fragmentary sectional views illustrating the joint between the interengaging ends of each pair of sections of the shell. 85

Heretofore it has been the practice to employ unprotected metal shells which were allowed to remain in the ground, and in a comparatively short time completely rotted away; or heavier metal shells were used and 90 withdrawn. But both practices are uneconomical. I have solved the problem by providing a comparatively inexpensive shell the features of which have inherent qualities giving it strength to offer maximum resistance to outside pressure, the shell being of thin sheet-metal, expanded metal or other mesh, with longitudinal corrugations extending continuously throughout the length of the pile. This corrugated reinforcing 95 member is indicated at 10. A shell of this nature when filled with a cementitious material adds considerable strength to the pile both as regards compression and shear, and it is suitable to meet the requirements where 100 the ground has a compactness offering little external pressure upon the shell.

In order to adapt the shell to offer maximum resistance to outside pressure, a series of steel rings 12 are preferably uniformly 110 spaced within the shell and connected by rivets 14 or other suitable means to the in-

ner curves 15 of the corrugations. These rings convert each corrugation into a beam, the tension element of which is the portion of the ring between the rivets, and the compression element the outward curve of the corrugation. This trussed shell is suitable for driving through very hard ground owing to the fact that the rings act as supports for the driving core if it and the shell are 10 tapered.

In order to afford a permanent protection for the metal and include the metal as a permanent reinforcement for the pile, I apply a cementitious coating or outside casing 16. 15 This cementitious coating is applied uniformly over the entire surface and in a manner to present a cylindrical perimeter.

In order to take care of internal strains and at the same time distribute the stresses 20 in the cementitious coating, I encircle my shell if made of expanded metal or other mesh, with a spiral length 40 of wire, and if the shell consists of smooth sheet metal, with either spiral wire or a comparatively 25 light-weight mesh, or both. The cementitious coating is afterward applied and the shell produced obtains the result above mentioned.

This outside coating has the effect of 30 converting the outside curves of the shell into a circumferential series of arches the lateral thrust of which in a circumferential direction relatively to the shell, is absorbed by the cement and the inward curves of the corrugations.

To meet certain requirements my improved pile shell is made in sections, as shown in Fig. 7, of straight cylindrical form instead of being tapered as shown in Fig. 1. 40 In this case the corrugated reinforcing metal 10 is projected beyond one end as at 17 and notched as at 18 to straddle the rivets 14 by which the rings are secured to the shell. This straight cylindrical sectional

45 form enables a pile of any required depth to be formed by first driving the shell-member illustrated in Fig. 1 or any pointed member and then adding sections such as illustrated in Fig. 7 until the required depth is 50 reached. If the ground being piled is of such compactness that a core must be used, a member such as illustrated in Fig. 1 may be driven as a leading section or in fact any of the well known forms of pile points such as indicated at 125. The core may be then 55 withdrawn and the pile filled with concrete or other cementitious substance or sand, gravel or other material as may be required; after which a flat-ended core 200 is used,

60 with its lower end of a diameter corresponding with the interior diameter of the superimposed section. The form of core I prefer to use with a sectional shell consists of a head member 22 and an annular section 23 yielding connected to the head to form a

yielding part thereof posts 24 having sleeves 123 thereon supporting helical springs 124 bearing upon the underside of the head. The lower head of this core rests on the filling of the driven shell section while its 70 yielding annular member rests on the top of the next following shell section. This driving head transmits a large portion of the force of the impacts of the hammer directly to the filling of the driven section and 75 the annular member translates a minor portion of the force of the impacts into a substantially yielding progressive force acting upon the shell section and causing it, and through it the driven shell, to follow the 80 point and filling. The sleeves 123 serve to adjust the tension of the springs and consequently the resistance to the relative movement between the parts of the head, the effect being that different resistances in the 85 material through which the shell is passing, may be taken care of.

In order to reinforce the joints between the sections a ring 25 of sufficient width to overlap the joint is located at the top 90 of each section the projecting portion 17 of the reinforcement metal straddling the rivets 14 as above mentioned.

This design of shell is adapted to meet the requirements where a vertical reinforcement is necessary to take care of abnormal 95 external loads. This being effected any time before the shell is filled, by introducing rods 30 or wire 31 into the spaces within the corrugations.

A shell constructed as above described is 100 designed to meet any requirement and carry any load, and, furthermore, is adapted to offer maximum resistance to the pressure of the material into which it may be driven, 105 and sustains this pressure either when driven by a core which does not sustain it internally or after a tapered core has been withdrawn.

Although the mesh may be used in connection with expanded metal shells it may 110 in some cases be used with shells of plain sheet iron. In Figs. 1 and 2 the pile shell of plain sheet iron is illustrated, while in Fig. 3 a shell of expanded metal without 115 the wire mesh is shown, the construction shown in Figs. 4 and 5 being corrugated expanded metal with the use of wire mesh.

What I claim is as follows:—

1. A trussed hollow concrete pile-shell 120 consisting of corrugated metal with the corrugations running longitudinally and rigid annular stiffeners uniting the inner curves of the corrugations for the purpose of converting each corrugation into a beam, and 125 a cementitious coating for the corrugated metal.

2. A trussed concrete pile-shell consisting of metal longitudinally corrugated and a series of rigid rings within the shell, and 130

devices fastening the rings to the inner curves of the corrugations for the purpose of converting each corrugation into a beam to offer maximum resistance to outside pressure, and a cementitious coating for the corrugated metal.

3. A pile comprising sections of shell each consisting of a cementitious material and a longitudinal corrugated metallic member surrounding the same, an outer casing of cementitious material, the metallic member of each section projecting into the adjoining sections, annular stiffeners secured to the inner curves of the corrugations and adapted to convert each corrugation into a beam, longitudinal reinforcing members within the corrugations, and a cementitious filling for the said sectional shell.

4. A pile comprising sections of shell each consisting of a longitudinally corrugated

metallic member surrounding the same and having a series of rings within the same, devices securing the rings to the inward curves of the corrugations, the ring at one end being of sufficient width to lap the joint, an 25 outer casing of cementitious material, the metallic member of each section projecting into the adjoining section and having its projecting portion notched to straddle the devices fastening the end ring in place, and 30 a cementitious filling for the said sectional shell.

In testimony whereof I have signed my name to this specification in the presence of two witnesses.

GEORGE R. HECKLE.
